UNITED STATES PATENT OFFICE.

WILLIAM FRANKLIN DOWNING, JR., OF ST. CLAIR, AND CHARLES LEWIS WEIL, OF PORT HURON, MICHIGAN, ASSIGNEES TO DIAMOND CRYSTAL SALT COMPANY, OF ST. CLAIR, MICHIGAN, A CORPORATION OF MICHIGAN.

CONTINUOUS CENTRIFUGAL DRIER.

1,259,727.

Specification of Letters Patent. Patented Mar. 19, 1918.

Application filed June 22, 1917. Serial No. 176,422.

To all whom it may concern:

Be it known that we, WILLIAM F. DOWNING, JR., and CHARLES L. WEIL, both citizens of the United States of America, residing at St. Clair and Port Huron, respectively, in the county of St. Clair and State of Michigan, have invented certain new and useful Improvements in Continuous Centrifugal Driers, of which the following is a specification, reference being had therein to the accompanying drawings.

The invention relates to centrifugal driers such as are employed in the drying of salt and similar materials, and it is the object of the invention to obtain a construction in which the material may be continuously fed in and out of the centrifugal without interrupting the rotation thereof.

In the drawings:
20 Figure 1 is a vertical central section through the device;

Fig. 2 is a horizontal section on line 2—2

Fig. 1;
25 Fig. 3 is an enlarged section showing the differential drive for the feeding mechanism;

Fig. 4 is an elevation at right angles to Fig. 3.

A is the revoluble drum, which is formed of suitable material for permitting the passage of liquid therethrough while retaining the salt material. This drum is mounted upon a central shaft B by means of heads C, the lowermost of which is fast upon said shaft, said shaft being preferably suspended from a spherical bearing D which permits it and the drum to rotate around the true center of gravity. E is a pulley for imparting rotary motion to the shaft B. The upper portion of this shaft is hollow and is connected with a conduit F for introducing material into the drum, said material passing downward through the hollow shaft and being discharged through lateral openings G therein at the upper end of the drum.

45 With the construction as thus far described, it would be possible to introduce the salt or other material to be dried while the drum is rapidly revolving, but on account of the lack of fluidity of the material 50 it would not of itself feed downward

through the drum but would lodge in the upper portion thereof. It is therefore essential to provide a positive feeding mechanism for passing the material longitudinally through the drum and finally discharging 55 the same at the lower end. This we have provided for by mechanism of the following construction:

H is scraper or feeding member arranged within the drum, which as shown is in the form of a worm or spiral mounted upon a sleeve I engaging a shaft B. J is the tubular driving member for the worm which has an enlarged portion J' in the plane of the apertures G and peripherally perforated for the passage of the material therethrough. K is an enlargement in the member J outside of the drum, in which is arranged a differential or planetary gearing. As specifically shown, this gearing comprises an internal gear-wheel L keyed or otherwise rotatively connected with the shaft B, an internal gear-wheel M of different diameter connected to the casing K and a rotary member N journaled on an eccentric bearing O 70 having an external gear-wheel P in mesh with the internal gear-wheel L and an external gear-wheel Q in mesh with the internal gear-wheel M. The eccentric bearing O is formed upon a member R which is sleeved 80 upon the shaft B and is held from rotation. Inasmuch, however, as the shaft B is suspended from the spherical bearing D and is free to oscillate so as to rotate about its true center of gravity, it is necessary to provide 85 for this movement in the anchorage connection of the member R. Thus, as shown, the member R is provided with a flange S having laterally slotted ears T projecting therefrom and connected by pins U with vertical 90 slotted ears V on the stationary bearing member W. The ears T are spaced from each other so as to permit movement of the ears V longitudinally of the pin U, and springs X sleeved upon said pins serve to 95 yieldably hold the parts in normal position. The upper head C of the drum is journaled upon the member J intermediate the enlarged portions J and K of said member.

With the construction just described when the shaft B is revolving a planetary movement will be imparted to the member N due to the differential diameters of the pairs of intermeshing gear-wheels L P and M Q. This will drive the casing K at a different speed of rotation than that of the shaft B and through the medium of the member J will impart this movement to the sleeve I and worm H. Thus the drum may be revolved at high velocity while the rotation of the feeding worm is comparatively slow. As the periphery of this worm is in close proximity to the inner face of the drum the 10 salt or other material discharged in the upper portion of the drum will be slowly forced downward until it is finally discharged from the lower end thereof. With the construction as described the operating 15 of drying the salt or other material may be carried on continuously without interrupting the rotation of the drum, which has obvious advantages over the intermittent operation now commonly used. Furthermore 20 this feeding movement is imparted without interfering in any way with the freedom of the drum and its suspension shaft to rotate about the true center of gravity.

30 What we claim as our invention is:

1. The combination with a centrifugal drum, of a driving shaft for revolving and suspending the same, free to rotate about its true center of gravity, the upper portion of said shaft being hollow for the feeding of the material into the drum, mechanism mounted within the drum for positively feeding the material therethrough, and means for driving said feeding mechanism, 35 permitting free rotation of said drum about its true center of gravity.

2. The combination with a continuously rotating centrifugal drum; of means for introducing material into one end of said drum, mechanically operated feeding mechanism for advancing the material through said drum from its point of introduction to the point of discharge, and means for driving said feeding mechanism permitting of the free rotation of said drum about its true 45 center of gravity.

3. The combination with a centrifugal drum, of means for suspending said drum permitting the rotation thereof about its true center of gravity, means for introducing material into one end of said drum, mechanical means mounted within the drum for positively advancing the material therethrough, and a differential drive mechanism 50 for said mechanical feeding means permitting the free movement of the drum to rotate about its center of gravity.

4. The combination with a centrifugal

drum, of means for suspending said drum permitting it to rotate about its true center of gravity, mechanism mounted within the drum for mechanically feeding material therethrough, and a differential gearing connecting said mechanism with said drum to produce a differential rotation thereof.

5. The combination with a centrifugal drum of a driving shaft for revolving and suspending the same, free to rotate about its true center of gravity, the upper portion of said shaft being hollow for the feeding of the material into the drum, mechanism mounted within the drum for positively feeding the material therethrough, a differential gearing mounted on said shaft and forming a driving connection between the same and the mechanism within the drum, and an anchorage for said differential gearing permitting the free turning of the shaft in balanced rotation about its center of gravity.

6. The combination with a centrifugal drum of a shaft forming a driving and suspension means for said drum and having a pivotal bearing permitting oscillation to rotate about the true center of gravity, the upper end of said shaft being hollow for the feeding of the material to the drum, a worm scraper mounted on said shaft within the drum and adapted to mechanically feed the material therethrough, and means for differentially rotating said scraper comprising a differential gearing mounted upon said shaft and forming a connection intermediate the same and said worm and an anchorage for said differential gearing having an articulated connection therewith permitting the free oscillation of the shaft and holding one member of said gearing from rotation.

7. The combination with a centrifugal drum, of a driving shaft for revolving and suspending the same free to rotate about its true center of gravity, means for introducing material into one end of said drum, mechanism mounted within the drum for positively feeding the material therethrough, a differential gearing mounted upon said shaft and forming a driving connection between the same and the mechanism within the drum, and an anchorage for said differential gearing permitting the free turning of the shaft in balanced rotation about its center of gravity.

8. The combination with a centrifugal drum, of a shaft forming a driving and suspension means for said drum and having a pivotal bearing permitting oscillation to rotate about the true center of gravity, means for introducing material into one end of said drum, a worm scraper mounted on said shaft within the drum and adapted to mechanically

feed the material therethrough, and means for differentially rotating said scraper comprising a differential gearing mounted upon said shaft and forming a connection intermediate the same and said worm, and an anchorage for said differential gearing having an articulated connection therewith per-

mitting the free oscillation of the shaft and holding one member of said gearing from rotation. 10

In testimony whereof we affix our signatures.

WILLIAM FRANKLIN DOWNING, JR.
CHARLES LEWIS WEIL.
